UNITED STATES PATENT OFFICE

135,946

DESIGN FOR A LAMP

Paul S. Keeler, Reading, Pa.

Application March 23, 1942, Serial No. 106,289

Term of patent 3½ years

To all whom it may concern:

Be it known that I, Paul S. Keeler, a citizen of the United States, residing at Reading, in the county of Berks and State of Pennsylvania, have invented a new, original, and ornamental Design for a Lamp, of which the following is a specification, reference being made to the accompanying drawing, forming part thereof.

I claim:

The ornamental design for a lamp, as shown.

PAUL S. KEELER.
